FOUNTAIN PEN WITH MEANS FOR CONTROLLING THE FLOW THEREFROM

Bertram Cholet, Hasbrouck Heights, N.J.

Application February 1, 1956, Serial No. 562,756

3 Claims. (Cl. 120—48)

This invention relates to a fountain pen particularly adapted for use for drawing, writing and lettering.

The invention comprehends a fountain pen which provides convenient means for controlling and regulating the flow of any drawing or writing ink used with the pen.

Another object of the invention is to provide a pen having a needle for closing off the flow of the ink and with means adapted to be engaged by a tip of the finger of the user for moving the needle to open up and close off the flow of the ink and for controlling the flow of the ink during use thereof.

Still another object of the invention is the provision of a slide member mounting the needle for reciprocatory movement toward and away from the ink discharge passageway and which slide member is disposed adjacent to the lower end of the pen in convenient position for manipulation thereof by the tip of one of the fingers holding the pen.

With the foregoing and other objects in view, reference is now made to the following specification and accompanying drawings in which the preferred embodiment of the invention is illustrated.

In the drawings:

Fig. 1 is a perspective view of a fountain pen in accordance with the invention.

Fig. 2 is an enlarged view in elevation showing the parts in separated juxtaposition and a fragmentary portion of the handle in section.

Fig. 3 is an enlarged longitudinal vertical sectional view thereof with the handle omitted.

Fig. 4 is an enlarged transverse sectional view taken approximately on line 4—4 of Fig. 3.

Fig. 5 is a side view of a modified form of fountain pen constructed in accordance with the invention.

Fig. 6 is an enlarged vertical sectional view taken approximately on line 6—6 of Fig. 5.

Fig. 7 is an enlarged transverse sectional view taken approximately on line 7—7 of Fig. 6.

Fig. 8 is a view in elevation of a modified form of fountain pen constructed in accordance with the invention and showing a fragmentary portion of the handle member in section.

Fig. 9 is an enlarged transverse sectional view taken approximately on line 9—9 of Fig. 8.

Referring to the drawings by character of reference, the pen may be of any desired character adapted to be conveniently held for drawing, writing and lettering and as illustrated in Figs. 1 to 4 inclusive of the drawings, a handle member 10 is provided to which an ink holder 11 is affixed in prolongation of the lower end thereof. The ink holder 11 consists of a cylindrical upper section 12 and a conical shaped lower section 13. The upper section 12 is formed with reduced upper and lower ends 14 and 15 which are exteriorly threaded for threadedly engaging the interiorly threaded ends 16 and 17 of the handle member 10 and the conical shaped lower section 13 respectively to secure the parts together.

The upper section 12 is formed with an opening 18 for

2

filling the pen with ink which is contained in the conical shaped portion 13. This portion terminates at its lower end in a reduced cylindrical extension 19 having a restricted passageway 20 for the flow of the ink. The lower end or tip 21 of the cylindrical extension 19 constitutes a stylus for drawing, writing or lettering. Located within the ink holder 11 is a needle 22 having a blunt lower end 23 which is of a diameter slightly smaller than the flow passageway 20 to permit of the movement of the needle axially of the ink holder for engagement of the lower end thereof in the ink passageway as indicated in Fig. 3 of the drawings to close off the flow of ink from the pen. The needle 22 is mounted for axial reciprocatory movement longitudinally of the holder 11, the upper end of the needle being somewhat larger in diameter than the lower end and fittingly engaging a bushing 24 in the reduced upper end 14 for guidedly mounting the needle.

In order to permit of the convenient movement of the needle to control the flow of the ink during use of the pen and for closing off and opening up the flow of the ink, a slide 25 is provided which is affixed to the needle and protrudes through openings in the wall of the upper section 12 in convenient location for engagement by one of the fingers of the hand grasping the pen. Thus when the pen is used, the slide 25 may be manipulated by the finger to move the needle 22 toward and away from the lower section 13 to control the flow of the ink. When the drawing, writing or lettering is completed, the slide is moved by the finger to close off the flow through the flow passageway 20.

The slide 25 consists of a rebent spring shown in plan in Fig. 4. The opposite legs are formed with inwardly offset portions 26 and 27 which portions engage through slots 28 and 29 in opposite sides of the needle 22. This retains the needle in fixed association with the slide. The slide protrudes through oppositely disposed openings 30 and 31 in the upper section 12 above the feed opening 18. Either end of the slide 25 may be engaged by the finger for manipulating the needle 22.

The holder may be adjustably connected with the handle member in order to dispose the holder in any desired angular position with reference thereto as shown in Figs. 5 to 9 inclusive of the drawings. In this form of the invention the ink holder 35 consists of a cylindrical upper section 36 and a conical shaped lower section 37 which is secured to the conical shaped lower end portion 38 of the cylindrical upper section 36. The cylindrical upper section is formed with a wing 39 which engages between the bifurcated ends 40 of the handle member 41. A screw stud 42 secures the wing in position and permits of the adjustment of the holder 35 to any desired angular position with reference to the handle 41.

The upper section 36 is formed with an opening 43 for filling the pen with ink which is contained in the lower portion thereof. The conical shaped lower section 37 is formed with a cylindrical extension 45, the lower end or tip 46 thereof forms a stylus for making relatively wide lines. The conical shaped lower section 37 together with the cylindrical extension 45 are provided with a restricted passageway 47 for the flow of the ink.

Located within the ink holder 35 is a needle 48 similar to the needle 22 in the previous form of the invention. The needle 48 is formed with a blunt lower end 49 which is of a diameter slightly smaller than the flow passageway 47 to permit of the movement of the needle axially of the ink holder for engagement of the lower end thereof in the ink passageway to close off the flow of the ink. The needle is mounted for axial reciprocatory movement longitudinally of the holder 35 with the upper end thereof slidably protruding through a cap 50 which threadedly engages the upper end of the cylindrical upper

section 36 to close the same. A slide 51 is provided which is similar to the slide 25 in the previous form of the invention and is formed with inwardly offset portions 53 and 54 extending through slots 55 and 56 in opposite sides of the needle 48 for retaining the needle in fixed association with the slide. The slide protrudes through oppositely disposed openings 58 and 59 in the cylindrical upper section 36 above the filling opening 43 with the opposite ends of the slide in convenient position for engagement by one of the fingers of the hand holding the pen for manipulation thereof to impart reciprocatory movement to the needle.

In the form of the invention illustrated in Figs. 8 and 9 of the drawings, the ink holder 60 is adapted to be releasably affixed to the handle member 61 in place of the pen point of the usual type of writing pen. The ink holder 60 similarly consists of a cylindrical upper section 62 and a conical shaped lower section 63. The upper section 62 is preferably fashioned from a strip of thin sheet metal which is rolled into cylindrical formation with the ends of the strip secured together in overlapping relation.

The upper section 62 is formed with an upwardly extending tongue 64 which together with the upper end of said section fits within the recessed lower end of the handle member 61. The said section is also formed with an ink feed opening 65 and with oppositely disposed slots 66 through which protrudes a slide 68 for manually moving a needle 69 for regulating the flow of the ink. The slide 68 consists of a rebent flat spring which extends through a slot 70 in the side of the needle 69 for retaining the needle in fixed association with the slide.

The conical shaped lower section 63 constitutes the receptacle for holding the ink and is provided with a cylindrical extension 74 having a passageway for the flow of the ink similar to the flow passageways in the previous forms of the invention. The needle 69 is mounted for guided sliding movement in aligned openings 71 in inwardly directed tongues 72 formed integrally with the cylindrical upper section 62 and bent inwardly into overlapping relation.

It is to be understood that the slots in which the slide is slideable in each of the forms of the invention are of sufficient length to permit of the movement of the needle so that the needle may be moved to dispose the lower end thereof in protruding relation from the ink holder whenever the use of the pen is discontinued and when the pen is used again, the slide may be moved upwardly to dispose the lower end of the needle sufficiently above the flow passageway to permit of the flow of the ink therethrough. The slots are of a width that the slide frictionally engages the opposite walls thereof so as to retain the slide in any desired set position therein. The slides in the several forms being positioned adjacent the lower ends of the handle members, respectively, as shown in Figs. 1, 5 and 8 of the drawings, are conveniently located for engagement by the tip of the index finger of the hand holding the pen so that when the pen is being used, the slide may be manipulated to provide finger tip control of the flow of the ink.

While the preferred forms of the invention are shown and described herein, it is to be understood that the same are not so limited but shall cover and include any and all modifications of the claims which fall within the purview of invention.

What is claimed is:

1. In a fountain pen of the character described, a handle member, a hollow ink holder affixed to said handle member and having a reduced passageway of uniform area in cross-section throughout its length for the flow of the ink through the lower end thereof, said holder having an opening for feeding ink thereto, a needle having an end portion of uniform cross-sectional area to snugly and

slideably fit said passageway, means located wholly above said passageway in said holder mounting said needle for guided movement to dispose said end portion thereof in said passageway and in a position in spaced relation from the inner end thereof for controlling the flow of the ink through said passageway, a slide affixed to said needle above said end portion thereof for movement of the needle with the slide, said holder having slotted means above said reduced passageway through which said slide protrudes, said slide projecting outwardly beyond said holder in convenient position to be actuated by the tip of one of the fingers of the hand holding the pen during use for imparting movement to the needle for controlling the flow of the ink through the flow passageway, and said slide frictionally engaging said slotted means for disposing the slide in any desired set position.

2. In a fountain pen of the character described, a handle member, a hollow ink holder affixed to said handle member and having a reduced passageway of uniform area in cross-section throughout its length for the flow of the ink through the lower end thereof, said holder having an opening for feeding ink thereto, a needle having an end portion of uniform cross-sectional area to snugly and slideably fit said passageway, means located wholly above said passageway in said holder mounting said needle for guided movement to dispose said end portion thereof in said passageway and in a position in spaced relation from the inner end thereof for controlling the flow of the ink through said passageway, a friction slide affixed to said needle above said end portion thereof for movement of the needle with the slide, said holder having slotted means in opposite sides thereof above said reduced passageway through which said slide protrudes, said slide projecting outwardly beyond said holder on opposite sides thereof in convenient position to be actuated by the tip of one of the fingers of the hand holding the pen during use for imparting movement to the needle for controlling the flow of the ink through the flow passageway, and said slide frictionally engaging said slotted means for disposing the slide in any desired set position.

3. In a fountain pen of the character described, a handle member, a hollow ink holder affixed to said handle member and having a reduced passageway of uniform area in cross-section throughout its length for the flow of the ink through the lower end thereof, said holder having an opening for feeding ink thereto, a needle having an end portion of uniform cross-sectional area to snugly and slideably fit said passageway, means guidedly mounting said needle for movement from a position in which said end portion thereof is arranged in said reduced passageway for closing off the flow of ink therethrough to a position in which said end portion is spaced from the upper end of the passageway to permit of the flow of ink therethrough, a slide affixed to said needle above said end portion thereof for movement of the needle with the slide, said holder having slotted means above said reduced passageway through which said slide protrudes, said slide projecting outwardly beyond said holder in convenient position to be actuated by the tip of one of the fingers of the hand holding the pen during use for moving the needle in varying spaced relation from said passageway for varying the flow of the ink therethrough, and said slide frictionally engaging said slotted means for disposing the slide in any desired set position.
